UNITED STATES PATENT OFFICE.

MAX DUNNEBIE, OF NEUWEID-ON-THE-RHINE, GERMANY, ASSIGNOR TO BALTIMORE PAPER COMPANY, OF KANSAS CITY, MISSOURI, A CORPORATION OF MISSOURI.

ENVELOPE-FOLDING DEVICE.

Application filed April 6, 1927. Serial No. 181,468.

This invention relates to folding devices used in connection with envelope machines and more particularly to apparatus such as is used for folding the end flaps of an envelope.

It is a purpose of the invention to provide new and improved means for folding the end flaps of envelopes, comprising rotatable members which supplant the reciprocating means previously employed. It is particularly desirable to eliminate the reciprocating means to reduce vibration in the machine and to reduce the wear and tear on the same.

More particularly it is a purpose of my invention to employ rotating disc-like members co-operating with stationary straight edged members to fold over the end flaps of said envelopes, thus simplifying the construction of machines of this character and reducing the number of moving parts thereof.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a perspective view of my improved end flap folding mechanism showing a portion of the machine, with which the same is associated.

Fig. 2 is a fragmentary longitudinal sectional view of a portion of said machine showing my improved folding device.

Fig. 3 is a fragmentary perspective view of one of the folding mechanisms showing the upper disc engaging with the flap.

Fig. 4 is a similar view showing the lower disc folding the flap to final position.

Referring in detail to the drawings, my improved end flap folding mechanism is shown as being applied to an envelope machine having a framework provided with the side members 10 and a transversely extending member 11 which may be secured to the framework in any desired manner as by means of the vertically extending members 12. Mounted for rotation in any suitable manner in the framework are the feed rollers 13 and 14, said rollers being mounted respec-

tively upon the shafts 15 and 16. The feed rollers are adapted to feed the envelope blanks 17 which have the end flaps 18 thereon toward the folding mechanism, a guide member 19 being provided for guiding said envelopes 60 toward the longitudinally extending guides 20. The longitudinally extending guides 20 are provided with upturned end portions 21 and are mounted upon the lower ends of rod-like members 22 which are adjustably mounted in the lateral extensions 23 on the adjustable bracket members 24, said adjustable bracket members being mounted for transverse adjustment on the machine on the transverse member 11. The adjusting means for 70 the rods 22 comprises the knurled nuts 25 screw-threadedly engaging with the screw-threaded portions 26 of the rods 22 and are held in adjusted position by means of the knurled lock nuts 27. The bracket members 75 24 are provided with cap members 28 secured thereto in any suitable manner as by means of members 29 and are held in adjusted position on the transversely extending member 11 by means of the headed set screws 30 which 80 have transversely extending bars 31 mounted therein to facilitate the turning thereof.

Mounted in spaced relation to the feed rollers 13 and 14 is a lower feed and guide roller 32 and upper pressure rollers 33. The roller 32 is mounted on a shaft 34 which is journaled in the machine framework and is driven in any desired manner from the main drive shaft of the machine while the rollers 33 are mounted on a shaft 35 provided on 90 the lower end of an arm 36, said arm 36 being mounted for swinging movement on a stationary transversely extending shaft 37. The shaft 37 also has mounted thereon in fixed position a curved finger 38 between 95 which and the arm 36 a compression spring 39 is mounted, said compression spring causing the rollers 33 to be yieldingly moved toward the roller 32. Mounted between certain of the rollers 33 on the arm 36 is the guide member 40 which co-operates with the guide member 19 in directing the envelope blanks into engagement with the guide member 20 and into engagement with the roller members 32 and 33. There is a guide member 20 at each 100 side of the machine and the adjoining edges 41 of the members 20 are thicker than the remote edges 42 thereof, said remote edges being beveled so as to provide a thin folding edge for the flaps 18.

Co-operating with the members 20 to move the flaps 18 into a position substantially perpendicular to the body portion of the blanks 17 are the reciprocable folding members 43, 5 said members being mounted on upwardly extending arms 44 on the shaft 45 being held in fixed position on said shaft by means of the set screws 46. The shaft 45 is mounted on arms 47 which oscillate to give an arcuate 10 reciprocating movement or oscillating movement to the members 43, said members 43 being provided with a curved edge portion 48 and being arranged in converging relation to each other as shown in Fig. 1 so that as said members are moved upwardly, the flaps 18 of the envelopes will be bent around the tapered edges 42 of the guide members 20 and will be substantially perpendicular to the body portions thereof when they reach the 15 position shown in Fig. 1. After the blanks leave the members 43 the same pass between the rollers 32 and 33 and are fed by said rollers to the rotatable folding mechanism.

Said rotatable folding mechanism is driven 20 by means of the transversely extending shaft 49 which is mounted in the bearings 50 provided in the cap members 28 and in the bearing members 51 provided on the standards 52 which are provided with feet 53 secured to 25 the side frame members 10 in any suitable manner as by means of the securing members 54. The shaft 49 is driven in any suitable manner as by means of the chain 55 operating over the sprocket wheel 56 mounted in fixed position on the shaft 49 and over the sprocket wheel 57 mounted in fixed position 30 on the shaft 34.

Each of the cap members 28 of the brackets 24 is provided with a downwardly and forwardly extending bracket portion 58 and each 40 of said bracket members 58 is provided with a bearing member 59 at the free end thereof in each of which a vertically extending shaft 60 is rotatably mounted. Each of the shafts 60 is rotated by means of a spiral gear 61 keyed thereto which meshes with a spiral gear 62 keyed on the shaft 49. The gears 61 are provided with downwardly extending sleeve portions 63 which engage with the 45 upper surface of bearing members 59 and said bearing members are provided with downwardly extending reduced portions 64 upon which the bracket member 65 is secured, said bracket member 65 being held in fixed 50 position thereon by means of the set screw 66. Mounted on each of the shafts 60 to rotate therewith, said shafts rotating in opposite directions, as will be obvious from Fig. 1, are a pair of spaced disc-like folding members 67 and 68, the members 67 and 68 being each provided with hub portions 69 by means 55 of which the same are secured in adjusted position on the shafts 60 upon which the same are mounted, the same being held in adjusted position by the set screws 70. Each

of the discs 67 is provided with a cut away portion 71 providing the substantially radially extending edges 72 and 73, the edges 73 serving as folding edges and each co-operating with the thinned edge 42 of the adjoining guide member 20 to bend the flap 18 engaging therewith into a position so that the same extends at an oblique angle to the body portion 17 of the blank. Thus the edges 73 of the members 67 fold the flaps 18 on opposite sides of the blank toward each other at an oblique angle over and around the member 20 at each side of the machine. The members 68 are each provided with a cut away portion 74 which is of greater extent 80 than the portion 71, thus providing a greater angle between the edges 75 and 76 provided on the disc-like member 68 due to the cut away portions 74. The edges 72 and 75 are arranged so that they coincide substantially 85 in a vertical direction to provide for the flap 18 to pass into the spaces provided by the openings 71 and 74. The edge 76, however, lies in such a position that it engages with the flap 18 subsequent to the engagement of 90 the edge 73 with the flap 18 and completes the folding of the flap 18 around the thinned edge 42 of the member 20. Thus the rotatable disc-like members 68 rotating in opposite directions at opposite sides of the blank, fold 95 the flaps 18 toward each other substantially in parallelism to the body portion of the blank 17.

The member 68 is located closely adjacent to the member 20 at each side of the machine 100 to thus fold the flap 18 firmly against the guide member 20 as the member 68 passes over the same, the member 67 having previously passed over the flaps 18 to move the same into an oblique angular position and hold them in such position until the edge portion 76 engages therewith. Mounted in spaced relation to the rollers 32 and 33 and on the opposite side of the rotatable folding members 67 and 68 therefrom are the rotatable rollers 77 and 78, by means of which the blanks are engaged to move the same away from the folding mechanism. In order to guide the blanks with the end flaps in folded condition, toward the rollers 77 and 78, the 105 guide members 79 are provided. Said guide members 79 are rectangular plate-like members having upturned curved corner portions 80 on the near sides thereof, said members being preferably beveled off on the sides 110 thereof toward the rollers as indicated at 81, and the guides 20 extending under said guides 79. The guide members 79 are adjustably mounted on the machine by means of the rod-like members 82 extending upwardly therefrom, which engage between the clamping arms 83 extending outwardly from the bracket 65, said arms being provided with partially circular grooves 84 for receiving the member 82 and with a clamping member 85 115

for drawing said arms 83 into clamping relation with the member 82. The members 43 are preferably cut away on an arcuate line as indicated at 86 so as to accommodate the roller 32 and so that the envelope blanks will leave the member 43 closely adjacent the rollers 32 and 33.

What I claim and desire to secure by Letters Patent is:

10. 1. In an envelope machine, a folding mechanism comprising a pair of rotatable disc-like members mounted in superposed relation and successively engaging with a flap to fold the same toward the body portion of an envelope.
15. 2. In an envelope machine, a folding mechanism comprising a pair of rotatable disc-like members mounted in superposed relation, said disc-like members having cut away portions providing edges successively engaging with a flap to fold the same toward the body portion of an envelope.
20. 3. In an envelope machine, means for conveying an envelope blank, means engageable with the blank for upending a flap, and members rotatable on a common axis, successively engaging the upended flap to fold the flap.
25. 4. In an envelope machine, a table, means for moving an envelope blank along the table, a reciprocating member engageable with the blank to bend a flap thereon, and members rotatable in planes parallel with the table successively engageable with the flap to fold the flap.
30. 5. In an envelope machine, means for conveying an envelope blank, means engageable with the blank to bend a flap thereon, and a rotatable member having a recess into which the flap is projected, and a blade portion at the edge of the recess engageable with the flap to fold the flap.
35. 6. In an envelope machine, means for conveying an envelope blank, means engageable with the blank to bend a flap thereon, and members rotatable on a common axis having surfaces of different angularity successively engaging the flap to fold the flap.
40. 7. In an envelope machine, means for conveying an envelope blank, means engageable with the blank to bend a flap thereon, and a plurality of disks rotatable on a common axis provided with recesses for receiving the flap and having offset rear edge portions for successively engaging the flap to fold the flap.
45. 8. In an envelope machine, a horizontal table, means for moving an envelope blank along the table, a stationary folding guide, a reciprocable member for bending the blank over the guide to form a flap, and spaced members rotatable on an axis perpendicular to the table, successively engaging the flap to fold the flap.
50. 9. In an envelope machine, a horizontal table, means for moving an envelope blank along the table, a stationary folding guide, a reciprocable member for bending the blank over the guide to form a flap, spaced members rotatable on an axis perpendicular to the table, successively engaging the flap to fold the flap, and means suspending said folding members above the table.
55. 10. In an envelope machine, a horizontal table, a guide suspended over the table, means for moving an envelope blank between the guide and table, a vertically reciprocable member engageable with the blank from beneath to bend a flap over the edge of the guide, means suspending a shaft over the table, means for rotating the shaft, spaced members fixed on the shaft having blade portions of different angularity successively engageable with the flap to fold the flap.
60. 11. In an envelope machine, a horizontal table, a guide suspended over the table, means for moving an envelope blank between the guide and table, a vertically reciprocable member engageable with the blank from beneath to bend a flap over the edge of the guide, means suspending a shaft over the table, means for rotating the shaft, spaced members fixed on the shaft having blade portions of different angularity successively engageable with the flap to fold the flap, a bracket on said shaft, and a guide on said shaft engageable with the flap to press the flap to the body of the blank.

In testimony whereof I affix my signature.

MAX DUNNEBIER.
